HELICOPTER

Buford J. Schramm, Mesa, Ariz., assignor to Monarch
Luggage Co., Inc., Brooklyn, N.Y., a corporation of
New York

Filed Oct. 3, 1967, Ser. No. 8,848

Term of patent 14 years

Int. Cl. D12—07

U.S. Cl. D71—1

Fig. 1

FIG. 1 is a quarter-front perspective of a helicopter showing my new design;

FIG. 2 is a side elevation; and

FIG. 3 is a top plan view with rotor blade fragmentarily shown and the starboard landing gear omitted for ease of illustration.

I claim:

The ornamental design for a helicopter, as shown and described.
